COIN CONTROLLED APPARATUS

Walter A. Bockisch, Chicago, Ill., assignor to
Western Electric Company, Incorporated, New
York, N. Y., a corporation of New York

Application July 11, 1936, Serial No. 90,087

4 Claims. (Cl. 194—16)

This invention relates to coin controlled apparatus, and more particularly to telephone coin collectors for use at public pay stations.

In certain types of telephone coin collectors the user tentatively deposits a coin which is subsequently collected or refunded by the central office operator, depending upon whether or not the desired telephone connection is obtained. Thus, in the apparatus disclosed in O. F. Forsberg U. S. Patent 1,043,219, issued November 5, 1912, the deposited coin is temporarily held upon a coin trap which is supported by a pivoted vane under the control of an electromagnet. If the pivoted vane is moved by the electromagnet in one direction the deposited coin is collected, while if it is moved in the opposite direction the coin is refunded and the direction this vane is moved depends upon which direction the current is made to flow through the electromagnet. In apparatus of this type, deposit of a coin or token is necessary before the substation can signal the central office operator. Usually the connection is made by means of a trigger mounted in the path of the deposited coin and caused to operate a line circuit switch when actuated by the passing coin.

An object of this invention is to provide improved and simplified apparatus for indicating the deposit of a coin in a coin controlled apparatus.

In accordance with one embodiment of this invention the coin chute of a telephone coin collector is provided with a hinged coin trap which is deflected a predetermined distance from its normal position by deposit of a coin thereon. An insulated lug projects from the trap through an opening in the chute wall and engages a pair of line switch contact springs mounted on the outside of the chute. The lug separates the springs when the trap is in its normal position and is shifted when the trap is deflected by a coin which permits the springs to complete a circuit signalling the coin deposit to a central office operator.

Other objects and advantages of this invention will be apparent from the following detailed description taken in conjunction with the appended drawing, in which—

Fig. 1 is a perspective view of a portion of a telephone coin collector showing a mechanism for controlling a line circuit responsive to the position of a coin arresting trap in the apparatus, embodying the invention;

Fig. 2 shows a coin trap, coin directing vane and contact springs in their normal positions;

Fig. 3 shows the relative positions of the coin trap, vane, and contact springs after a coin has been deposited and before it has been released by the electromagnet;

Fig. 4 shows the position of the apparatus of Fig. 3 after the electromagnet has been operated to release the deposited coins;

Fig. 5 shows the relative positions of the apparatus during the return stroke of the coin directing vane after the electromagnet has been deenergized to restore the mechanism to normal, and

Fig. 6 is a sectional view of the apparatus in Fig. 5 taken along the line 6—6.

In the operation of the telephone coin collector described herein a coin deposited by any person wishing to use the equipment traverses a coin chute and drops into a coin hopper 15, coming to rest on a coin trap 16 extending across the coin passageway. The coin trap, which is provided with a counterweight 17, is pivotally mounted and while supporting a coin rests against a roller 18 on a vertical vane 19 mounted on pivots 20 at its lower end.

A coin passage below the trap is divided into two channels; a refund chute leading to an opening where coins are accessible from outside the collector housing and a collect chute leading to a cash compartment within the housing. As explained in the Forsberg patent, if the vertical vane is moved to close the collect passageway, dropping of the trap will allow the deposited coin to fall in the refund chute, while if the vane is moved to close the refund chute dropping of the trap will allow the deposited coin to be diverted into the chute leading to the cash compartment. The apparatus so far described is similar to that disclosed in the Forsberg patent.

In accordance with a feature of this invention a pair of tensioned elongated contact springs 21 and 22 are mounted vertically on the rear outside wall of the coin hopper 15. The springs are secured to a bracket arm 23 extending from the hopper housing by means of screws 24 threaded into the bracket arm. The springs are insulated from one another and from the mounting bracket with suitable insulating material 25. Each spring member is provided with a terminal 26 and 27 at the mounting end which is connected to lead wires (not shown) running to the central office as described in the Forsberg patent.

The contact springs extend vertically downward and parallel to the hopper wall with their unsupported ends approximately opposite the

horizontal position of the coin trap. A cam or lug 28 made of insulating material and having an oval cross-section projects from the edge of the trap opposite the counterweight. A suitable opening is provided in the hopper housing to permit the projecting lug to engage the free ends of the contact springs which are formed to receive the lug between them and hold it frictionally.

10 The free end portions of the two contact springs are tapered with reference to one another so that the entering lug will spread the springs apart. Immediately above the tapered end portions the springs are shaped to form a pair of 15 parallel adjacent faces 29 and 30. On the inside of each of these faces is a coating or disk 31 of gold, silver, or other metal suitable for electrical contacts, welded or otherwise secured thereto. These contact disks are joined and separated in 20 accordance with the position of the insulated lug projecting from the trap to complete and interrupt the electrical circuit through the contact springs.

In a complete cycle of operation the coin trap 25 assumes four significant positions as shown in Figs. 2, 3, 4, and 5. Normally, it is elevated to its highest position, shown in Fig. 2, and retained there by friction contact between the projecting lug and the line switch contact springs. In this 30 position the lug holds the contact disks apart and the line circuit is consequently open. When a coin 32 is deposited in the instrument the weight of the coin on the trap overcomes this frictional resistance and deflects the trap to its second position against the roller on the coin directing vane as shown in Fig. 3. This movement shifts the lug downward sufficiently in the tapered spring arms to permit the springs to converge under their contained tension and join the contact disks, thus 40 completing the circuit through the springs and the line running to the central office to signal the coin deposit.

At an appropriate time the coin collecting or refunding mechanism is actuated by the central 45 office operator. This is done by rotating the vane on its pivots, as previously described, which causes the trap to drop under the weight of the coin into its third position, shown in Fig. 4. A suitable mechanism for actuating the coin directing vane is disclosed in the Forsberg patent and 50 can be connected to the vane by a suitable link 33.

After the coin is released from the trap the vane is returned to a vertical position by the actuating mechanism. During this motion the roller 55 on the vane and the counterweight on the trap cooperate to raise the trap to a horizontal position. In order to break the signalling circuit through the contact springs it is necessary to elevate the trap to its normal position above the 60 roller. This is accomplished by means of cams 34 hinged to the bottom of the trap and constructed to engage the vane on its return stroke. A detailed description of these cams and their operation is shown in the copending application 65 of M. L. Landreth, Serial No. 90,085, filed July 11, 1936.

As shown in Fig. 6 the cam has a short arm 35 and a relatively long arm 36 joined at approximately 90°. When the coin directing vane is rotated to release the trap, it engages the long cam

arm which is free to swing on its pivot to avoid interference with the vane movement. On the return stroke of the vane, the long arm is held in its path by the short cam arm which engages the bottom of the trap. This causes the vane 5 to lift the trap to its normal or elevated position and forces the insulated lug between the tapered ends of the contact springs which separates the contact disks on the springs and opens the coin signalling circuit.

10 The construction described herein provides a simple and effective mechanism for signalling the deposit of a coin and conditioning the apparatus circuits when a coin is deposited. Operation of the line circuit is directly responsive to the deposit 15 of a coin in the apparatus, thus insuring positive and consistent performance, and the component apparatus required to control the circuit is reduced to a minimum.

Other adaptations of this construction will be 20 apparent and it is to be understood that the invention is limited only by the scope of the appended claims.

What is claimed is:

1. In a coin controlled apparatus, a coin chute, 25 a trap therein adapted to be deflected from its normal position by the weight of a coin deposited thereon, and a common means for holding the trap in its normal position and initiating a signal when a coin is deposited, comprising a pair of tensioned contact springs, and a lug of insulating material projecting from the trap for normally separating the tensioned springs and permitting the springs to engage when the trap is deflected by deposit of the coin.

35 2. In a coin controlled apparatus, a coin chute, a trap therein adapted to be deflected from its normal position by the weight of a coin deposited thereon, means for holding the trap in its normal position comprising a pair of tensioned 40 springs, and a lug on the trap for projecting between the tensioned springs and securing the trap in its normal position.

3. In a coin controlled apparatus, a coin chute, a trap in the chute adapted to be deflected by the 45 deposit of a coin thereon, a pivoted vane for normally arresting the deflection of said trap, a coin deposit signal switch having a pair of cooperating contact springs, a projecting lug of insulating material on the trap to normally separate the springs 50 and release the springs when the trap is deflected by deposit of a coin, means for pivoting the vane to drop the trap and collect the deposited coin, and means secured to the trap for engagement with the vane for restoring the trap to its normal 55 position.

4. In a coin controlled apparatus, a coin chute, a trap in the chute adapted to be deflected a pre-determined distance from its normal position by the deposit of a coin thereon, a pivoted vane for 60 normally arresting the deflection of the trap caused by the deposited coin, a coin deposit signal switch, a lug of insulating material projecting from the trap for contacting the switch, means for pivoting the vane to drop the trap and collect the deposited coin, and a hinged cam on the bottom of the trap to engage the vane on its return stroke after the coin is collected for returning the trap to its normal position.
